UNITED STATES PATENT OFFICE.

SAMUEL KLINE, OF TRENTON, NEW JERSEY.

DESIGN FOR A CHAIR.

SPECIFICATION forming part of Design No. 26,623, dated February 9, 1897.

Application filed October 20, 1896. Serial No. 609,471. Term of patent 14 years.

To all whom it may concern:

Be it known that I, SAMUEL KLINE, a citizen of the United States, residing at Trenton, in the county of Mercer and State of New Jersey, have invented and produced a new and original Design for Chairs, whereof the following is a specification, reference being had to the accompanying drawing, showing a part thereof.

10 The drawing is a side elevation of a chair, showing my design.

Said chair comprises a base A, and a frame B, mounted on said base, and provided with a seat D, back C, and a foot-rest E.

15 My present invention relates to the said frame B, the principal feature of my design being the contour of said frame, consisting in a broad upper portion B^X, forming sides or

arms for said seat-member D, and having an abrupt or substantially vertical front edge 20 B', and a sloping rear edge B², terminating in a narrow substantially horizontal basal portion b^X. The opening B³ in the said broad upper portion B^X is partly closed by vertical bars b³. The said horizontal basal portion b^X of said frame B is supplemented at its forward end by an upwardly-extending foot-rest member E^X.

What I claim is—

The design for a chair herein shown and described.

SAMUEL KLINE.
